UNITED STATES PATENT OFFICE.

ETHEL SHRADER, OF SALINA, KANSAS.

DRESS-SHIELD SUPPORTER.

1,348,754.

Specification of Letters Patent.

Patented Aug. 3, 1920.

Application filed June 17, 1919. Serial No. 364,814.

To all whom it may concern:

Be it known that I, (Miss) ETHEL SHRADER, a citizen of the United States, and a resident of Salina, in the county of

5 Saline and State of Kansas, have invented new and useful Improvements in Dress-Shield Supporters, of which the following is a specification.

This invention relates to dress shields 10 and an important object is to provide a means whereby the shields may be held in a desired position upon the wearer without necessitating their being sewed or stitched to the dress as is the present day general 15 practice.

A further object of the invention is to provide a means for retaining the shields in correct position which will not hinder or hamper the freedom of movement of the 20 body.

Other objects and advantages of the invention will be apparent during the course of the following description taken in connection with the accompanying drawings.

25 In the drawings, forming a part of the specification and wherein like numerals are employed to designate like parts throughout the same,

Figure 1 is a view showing the device embodying my invention applied,

Fig. 2 is a perspective view of the device,

Fig. 3 is a similar view to that of Fig. 2, certain elements thereof being detached, and,

35 Fig. 4 is an elevation of a separable fastener.

In the drawings, wherein for the purpose of illustration is shown a preferred form of my invention, the numeral 5 indicates a waist band having its ends detachably secured together by means of a separable fastener 6, which fastener may be in

40 the form of a button, buckle or clasp, as desired. The waist-band 5 is intended to encircle the waist of the wearer and is preferably formed from a non-elastic material such as tape or the like and is provided with diametrically opposed tabs 7 having eyelets

45 8 to which are secured retaining tapes 9 preferably formed of suitable elastic material. The tapes 9 are detachably secured by means of separable closures as indicated by the numeral 10 as a whole to the lower half of the shield 11 as clearly shown in

50 55 Figs. 1 and 2. The tapes 9 together with the waist-band 5 tend to retain the lower

half of the shield in close contact with the body of the wearer as is apparent and because of their elasticity freedom of movement of the body is permitted.

60

To the shield substantially intermediate its ends there is secured a back-band 12 formed from a suitable elastic material and to one of the shields there is secured a similar front-band 13 which is connected to the other shield by a separable fastener as shown at 14. To the upper half of each shield there is detachably secured, by means of a separable fastener as shown at 15, an arm band 16 adapted to encircle the upper 70 portion of the wearer's arm as clearly shown in Fig. 1. To each of the shields substantially intermediate the ends thereof there is secured a shoulder-band 17. The shoulder-band 17 and the arm band 16 are preferably 75 formed of suitable elastic material and serve to retain the upper half of the shield in close contact with the wearer's body as is apparent from Fig. 1.

To apply the device the waist-band 5 and 80 front-band 13 are separated by means of separable fasteners as shown at 6 and 14 respectively and the arms are inserted through the arm-bands 16 and the shoulder-bands 17. When the shields are in correct 85 position the waist-band and front-band may be fastened by means of their respective fasteners as shown at 6 and 14.

Should it for any reason be desired to omit the waist-band and the tapes 9, it is 90 only necessary to detach the tapes from the shields 11, and furthermore, should it be desired to employ only the back-band 12 and the front-band 13 together with the shoulder-bands 17 the arm-bands 16 may 95 be separated from the shields 11, employing only those elements shown in Fig. 3. Since the various elements indicated by the numerals 5, 9 and 16 are separable it is apparent that any one of these elements may 100 be omitted in use should their omission be found desirable because of the particular style of dress worn at the time of using the shield.

It is to be understood that the form of 105 my invention herewith shown and described is to be taken as a preferred example of the same, and that various changes in the shape, size and arrangement of parts may be resorted to without departing from the spirit 110 of the invention or the scope of the subjoined claim.

Having thus described my invention, what I claim as new and desire to secure and protect by Letters Patent of the United States, is:

- 5 A dress protector comprising a pair of shields, a waist-band, tabs secured to said waist-band, eyelets carried by said tabs, a pair of elastic tapes secured to each of said eyelets, means carried at the ends of said tapes for detachably securing the same to the dress shields for retaining a half of the shields flat and in contact with the body of the wearer, elastic shoulder-bands adapted to be detachably secured to the dress shields midway intermediate the ends there-
- 10
- 15

of, elastic arm-bands adapted to be detachably secured to one end of the shield whereby the one half of said shields are retained in contact with the arms of the wearer, a front-band and back-band adapted to encircle the body of the wearer for retaining the dress shields in close contact with the body of the wearer, said front-band and back-band being secured to said shields midway intermediate the ends thereof, and means for detachably connecting one end of said front-band to one of the shields. 20 25

ETHEL SHRADER.
